SOUVENIR PLAQUE

Julien Charles Louis Vanderput, Brussels, Belgium

Application July 28, 1948, Serial No. 147,812

Term of patent 3½ years

(Cl. D29—23)

To all whom it may concern:

Be it known that I, Julien Charles Louis Vanderput, citizen of the Kingdom of Belgium, residing at Woluwé-St. Lambert (Brussels), in the country of Belgium, have invented a new, original, and ornamental Design for a Souvenir Plaque, of which the following is a specification, reference being had to the accompanying drawings, forming part thereof.

The figure is a front perspective view of a souvenir plaque, showing my new design.

The back of the plaque is substantially plain.

I claim:

The ornamental design for a souvenir plaque, substantially as shown and described.

JULIEN CHARLES LOUIS VANDERPUT.
